UNITED STATES PATENT OFFICE.

ELLERY F. COFFIN, OF MUIRKIRK, MARYLAND.

CAR-COUPING.

SPECIFICATION forming part of Letters Patent No. 402,808, dated May 7, 1889.

Application filed March 14, 1889. Serial No. 303,243. (No model.)

To all whom it may concern:

Be it known that I, ELLERY F. COFFIN, a citizen of the United States, of America, residing at Muirkirk, in the county of Prince George's and State of Maryland, have invented certain new and useful Improvements in Car-Couplings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of car-couplers in which the coupling pin or pins are supported by a sliding spring-pressed plate or follower and seated in the link by spring-pressure when the follower is moved aside.

The object of my invention is to couple cars by the simultaneous action of two coupling-pins moved in opposite directions by a spring or springs.

To this end the invention consists in novel features of construction and combinations, to be hereinafter described and claimed.

In the accompanying drawings, Figure 1 is a perspective view of a coupler embodying my improvements. Fig. 2 is a longitudinal vertical section of the same. Fig. 3 is a vertical section through line $x-x$, Fig. 2. Fig. 4 is a section through line $y-y$, Fig. 2.

To the center of the end sill, a , of a car, A , is secured a heavy bolt, B , upon the forward end of which is mounted a cross-head, C , the hub c of which bears upon the face of said sill. From the ends of this cross-head C project rigid link-plates D , provided at their outer ends with apertures d for the reception of the coupling-pins of an adjacent car, and parallel with these link-plates are secured two grooved arms, E , within the grooves e of which are mounted sliding followers e' . Between the forward ends of these arms E and projecting through them is a hollow cylinder F , provided at its upper and lower sides with slots f , and mounted to slide within its opposite ends are coupling-pins F' , between the inner ends of which are confined coiled springs f' , exerting an outward pressure on the pins. These springs encircle guide-rods and are supported

laterally thereby. At the ends of the slots f of cylinder F are arranged friction rollers or pulleys f^2 , designed to guide a chain, f^3 , connected at its center to a pull-rod, G , and secured at its opposite ends to the inner ends of the pins F .

To the rear ends of the followers e' are secured guide-rods e^2 , the rear ends of which slide freely through openings in the cross-head, and encircling these guide-rods, between the followers and cross-head, are coiled springs e^3 , designed to force the followers toward the outer ends of the grooved arms E .

To opposite sides of the hub c of the cross-head C are secured eyes or staples c' , to which are secured the inner ends of chains C' . These chains are wound upon the hub c in opposite directions, the outer ends being removably secured to hooks a' , or other fastening devices projecting from the car.

In operation the chains C' will secure the coupling-head of one car in the position shown in the drawings, while the coupler on the adjacent car will be held in the opposite position—that is, with the grooved arms E uppermost to receive the ends of the link-plates D . In coupling, should two adjacent coupling-heads have the same position one must be reversed by means of its chains C' , in order that the link-plates D of one coupling-head may enter the grooves of the arms E of the other head. When the cars are brought together, the link-plates D of one car will enter the outer ends of the grooves of the arms E of the other car, and by forcing back the followers e' will free the pins F' and permit them to engage the pin-apertures d of the link-plates D . To uncouple, the pull-rod G is drawn upward, thus withdrawing the pins from the link-plates through the agency of the chain, and as the cars move apart the followers will move forward past the ends of the coupling-pins and confine them within their cylinder until the followers are again forced back to release them.

To suspend the operation of the coupler, I secure to the cylinder F , at each end of the slots f , a hinged latch, H , a projecting lug, h , on which is adapted to drop behind a shoulder on the inner end of each coupling-pin, thus holding the pins securely, even though

the followers be removed from in front of their outer ends. The object of this arrangement is to suspend the operation of one pair of coupling-pins when two couplers come together, it being supposed that one pair will couple the cars securely, and that by throwing the other out of use the cars may be uncoupled with greater facility, as only one rod will have to be operated instead of two—that is, the cars should all be coupled either by all the lower coupling-pins or all the upper ones, but not by both unless desired for some special purpose, as in a vestibuled train, to have the cars more securely and rigidly coupled, when both sets of pins—the upper and lower ones—may be used. In case of accident to one set of pins or link-plates on a coupler, the other set, or those on the adjacent car, can be used.

Having thus described my invention, what I claim, and desire to secure by Letters Patent, is—

1. The combination, substantially as described, of a car, a draft bar or bolt secured thereto, a cross-head adapted to rotate on said bolt and provided at its ends with link-plates and grooved arms, spring-pressed coupling-pins adapted to protrude through said arms, and spring-pressed followers arranged to hold the pins normally in their retracted position.

2. The combination, with a car and its draft-bolt, of a cross-head mounted to rotate on said bolt, means to lock the cross-head against rotation, link-plates and grooved arms projecting forward from the outer ends of the cross-head, a slotted cylinder secured between the outer ends of the grooved arms, spring-pressed coupling-pins seated within said cylinder and connected at their inner ends to a pull-rod, and spring-pressed followers adapted to close the outer ends of the cylinder or to be moved therefrom.

3. The combination, with a car, of a coupling-head provided with grooved parallel arms, a slotted cylinder having its ends seated in openings in said arms, spring-pressed coupling-pins seated in the outer ends of said cylinder, a pull-rod, chains connecting the inner ends of the pins with the pull-rod, and latches secured to the cylinder and adapted to engage shoulders on the pins to hold them against the outward pressure of their springs, substantially as described.

In testimony whereof I affix my signature in presence of two witnesses.

ELLERY F. COFFIN.
